DESIGN FOR A CLOTHES BRUSH

Ray Athol Paisley, Frederick, Md., assignor to Ox Fibre Brush Company, Inc., New York,
N. Y., a corporation of Delaware

Application June 22, 1938, Serial No. 77,979

Term of patent 14 years

To all whom it may concern:

Be it known that I, Ray Athol Paisley, a citizen of the United States, residing at Frederick, in the county of Frederick and State of Maryland, have invented a new, original, and ornamental Design for a Clothes Brush, of which the following is a specification, reference being had to the accompanying drawing, forming part thereof.

Figure 1 is a side elevation of a clothes brush showing my new design; Fig. 2 is a view of the under side of the brush, and Fig. 3 is an end view of the same.

I claim:

The ornamental design for a clothes brush,
substantially as shown.

RAY ATHOL PAISLEY.
